(57) **CLAIM**

The ornamental design for a spray can dispenser, as shown and described.

DESCRIPTION

FIG. 1 is a top perspective view of a spray can dispenser showing my new design.

FIG. 2 is an exploded top view thereof;

FIG. 3 is a bottom perspective view thereof;

FIG. 4 is an exploded bottom view thereof;

FIG. 5 is a top view thereof;

FIG. 6 is a front view thereof;

FIG. 7 is bottom view thereof;

FIG. 8 is a back view thereof;

FIG. 9 is a right view thereof;

FIG. 10 is a left view thereof;

FIG. 11a is a section view thereof, taken along the line 11-11 in FIG. 5; and,

FIG. 11b is a section view thereof, in an alternate position taken along the line 11-11 in FIG. 5.

The broken lines of FIGS. 1-11b illustrate portions of the spray can dispenser that form no part of the claimed design.
